UNITED STATES PATENT OFFICE.

FRANK W. EPPERSON, OF OAKLAND, CALIFORNIA.

DESIGN FOR A LIQUID DISPENSER.

Application filed March 9, 1929. Serial No. 30,414. Term of patent 3½ years.

To all whom it may concern:

Be it known that I, FRANK W. EPPERSON, a citizen of the United States, and a resident of the city of Oakland, county of Alameda, State of California, have invented a new, original, and ornamental Design for a Liquid Dispenser, of which the following is a specification, reference being had to the accompanying drawing, forming part thereof. The drawing is a perspective view of the liquid dispenser illustrating my new design.

I claim:

The ornamental design for a Liquid Dispenser substantially as shown.

FRANK W. EPPERSON.
